UNITED STATES PATENT OFFICE.

WALLACE SUMNER GRANGE, OF KIRKLAND, ILLINOIS.

LETTER-FILE AND CABINET.

SPECIFICATION forming part of Letters Patent No. 700,417, dated May 20, 1902.

Application filed October 24, 1899. Serial No. 734,668. (No model.)

To all whom it may concern:

Be it known that I, WALLACE SUMNER GRANGE, a citizen of the United States, residing at Kirkland, in the county of Dekalb and State of Illinois, have invented certain new and useful Improvements in Letter-Files and Cabinets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to letter-files and cabinet for the same; and it has for its objects to so construct the letter-file that when placed in position in the cabinet one side of the file will serve to close the open side of the adjoining file and the upper part of the front of the file will fit against a cleat or guard depending from the bottom of the horizontal partition or strip which divides the cabinet into horizontal compartments, the projecting top portion of the front fitting against the cleat or guard and the closed side of one file constituting a closure for the open side of the adjoining file and serving together to effectively exclude dust from the interior of the cabinet and from the several files forming a part of the same.

It has further for its object to so construct a file adapted to be used in the manner specified that a swinging clamp or clasp may be used, which in one position will serve to hold the letters securely in place in the file and allow the files to be placed side by side in the cabinet without interference from the clamp or clasp, said clasp or clamp in another position serving to support the file in an inclined position when removed from the cabinet, so that the contents of the file may be readily examined.

It has also for its object to so construct and apply the holding clasp or clamp that when it is in position to clamp the contents of the file it will be held in that position by resilient pressure, so that in releasing the clasp or clamp from its holding position the resiliency mentioned will assist in throwing the clasp or clamp from the front to the rear side of the file.

To the accomplishment of the foregoing and such other objects as may hereinafter appear, the invention consists in the construction and in the combination of parts hereinafter particularly described and then sought to be specifically defined by the claims, reference being had to the accompanying drawings, forming a part hereof, and in which—

Figure 1 is a perspective of the cabinet and files, showing one of the files partly drawn out. Fig. 2 is a perspective of one of the files. Fig. 3 is a perspective of a file with its paper-clamp thrown back. Fig. 4 is a vertical section through a portion of one of the partitions, showing the front wall of the file bearing against the guard on bottom of the partition; and Fig. 5 is a vertical cross-section through one of the files.

In the drawings the numeral 1 designates the letter-file, which is formed with the closed side 2 and an open side 3 and provided at its lower end on the open side with a cross piece or strip 4, which on its inner edge is preferably beveled, as shown at *a*, so as to form a rest for the papers and partition-cards when tilted forward in the examination of the letters or papers in the file, the cross piece or strip serving to prevent the papers and partition-cards from slipping out of the file at its lower portion.

For the purpose of holding the papers in the file a metal clasp or clamp (designated by the numeral 5) is employed. This clasp or clamp is made of stiff wire with its ends 6 bent at an angle to its sides 7 and its sides connected by a central portion 8, which preferably is curved or bent between its ends, so as to allow of a slight contraction when the clasp or clamp is pressed down between the opposite end walls of the file in order that the tension thus created by the resiliency of the wire will hold the clasp or clamp tightly in position between the end walls of the file and against the papers and partitions or division-cards in the file, this tension creating sufficient friction between the clamp and the end walls of the file to hold the clamp in its binding position, and thus constituting the clasp or clamp a frictional binding clasp or clamp, the width of the clasp or clamp being slightly greater than the width between the end walls, so as to create the necessary friction for holding the clamp in place.

The ends 6 of the frictional clasp or clamp are hinged or pivotally connected to the closed side 2 of the file by pivot-pins 9 or otherwise, so as to permit the clasp or clamp to be thrown 5 over the end of the file. The solid side 2 at its opposite corners is formed with the slots 10, which serve to receive the ends 6 of the clasp or clamp when the latter is thrown to the rear of the file, thus bringing the sides 7 10 and central portion 8 of the clasp into the position indicated in Fig. 3 of the drawings, so that the clasp or clamp will serve as a support to hold the file in an inclined position while its contents are under examination. The rear 15 wall 11 of the box is cut away on an incline, as shown, so as to enable the forefinger of the hand to be passed to the rear of one side of the friction clasp or clamp when in its binding position in order that the clasp may be 20 thrown into its open position by the pressure of the forefinger against its sides at the cut-away portion of the rear wall. By placing the forefinger against the side of the clasp, between it and the cut-away portion of the wall, 25 and giving the forefinger a sharp or quick movement up the incline of the rear wall the clasp or clamp will be released, and the rebound caused by the clamp distending when released from its binding pressure will cause 30 the clasp or clamp to swing sharply over the top of the file and to the rear thereof, and then by pressing the clamp backward, so as to bring its ends 6 substantially parallel with the solid side of the file, the clamp will be brought into 35 position to support the file in its inclined position.

The front end wall 12 of the file which constitutes the front of the file when the latter is in position in its cabinet is extended above 40 the solid wall 2 of the file, so that when the file is placed in the cabinet the extended top portion 13 of the front wall 12 will bear against a cleat or guard 14, which projects from the under side of the horizontal partition or strip 45 15 of the cabinet 16, said cleat or guard 14 lying back of the front edge of the strip or partition 15, so as to permit the projecting upper portion of the front wall 12 of the file to pass under the partition or strip 15 and bear against 50 the cleat or guard 14, the cleat or guard 14 thus excluding all dust from the interior of the cabinet and from the contents of the file.

The cabinet 16 may be made of any approved pattern and dimensions. When a 55 number of the files are placed within this cabinet, the closed wall of one file will rest against the open side of the adjoining file, and thus constitute a closure for the same, the side wall of the cabinet itself serving to close the open 60 side of the end file next thereto. It will be observed that the construction of file which I have described is specially designed for use with a cabinet and contemplates the use of a number of files in which the closed side of 65 one file will constitute a wall or closure for the open side of the adjoining file when a number of the files are placed in their cabi-

net, and is also designed for use with a cabinet which has the cleat or guard, against which the extended upper portion of the front 70 wall of the file will abut when the file is in position, so as to effectively exclude all dust from the cabinet and also from the file contents.

The front wall 12 of the file will be formed 75 with an opening 17 for the reception of a card to designate the contents of the file.

I have illustrated and described with particularity the preferred details of construction and arrangement of parts; but it is obvious that changes can be made in the details 80 and the essential features of my invention still be employed.

Having described my invention and set forth its merits, what I claim is— 85

1. The file and cabinet consisting of the cabinet provided with horizontal partitions or strips having depending cleats or guards on the under side thereof, said cleats or guards set back from the outer edges of the horizontal portions, and a number of files each formed with one open side and arranged so that the closed side of one will close the open side of the adjoining file, each file having its front end wall extended above its side wall and 95 formed with a shoulder below its top edge so as to have the extended portion bear against the face of the depending cleat or guard and the shoulder to lie below the under side of the depending cleat, substantially as described. 100

2. A cabinet paper-file having one open side with its front end wall extended above the closed side of the file, means for holding the contents of the file in place, and a cross-strip extending across the open side at the lower 105 end of the file, the top edge of said strip being below the middle portion of the file, substantially as described.

3. A cabinet paper-file having one open side with a cross piece or strip across its lower portion and a front and a rear wall and open top, its front end wall being extended above the closed side of the file, and a frictionally-held swinging clasp or clamp for holding the contents of the file in place, said clamp adapted 110 to be swung over to the rear of the closed side of said file to form a support therefor, substantially as described.

4. A cabinet paper-file having one open side and provided with a swinging resilient clasp 115 or clamp of greater width than the space between the end walls of the files whereby it is adapted to be held in clamping position by frictional contact with a part of the file, said clamp being pivotally secured to the file near 120 its upper portion to adapt it to be swung to the rear of the closed side of the file to constitute a support for holding the file in an inclined position, substantially as described.

5. A cabinet paper-file having one open side 130 and front and rear end walls, the rear end wall having an inclined cut-away portion, and a swinging resilient clasp or clamp adapted to be held in clamping position by frictional con-

tact with a part of the file, a part of said clamp lying adjacent to the inclined cut-away portion of the rear end wall of the file, whereby the finger may be inserted between said part 5 of the clamp and the cut-away portion of the end wall for the purpose of releasing the clamp substantially as described.

6. A cabinet paper-file having one open side and having the upper portion of the closed side slotted, in combination with a swinging clasp or clamp having its sides extended at an angle to its ends so as to adapt its ends to lie in the slotted portions of the closed side when the clasp or clamp is swung to the rear of the 10 closed side with the sides of the clamp in position to support the file in an inclined position, substantially as described.

7. A cabinet paper-file having an open and a closed side, and means for bearing against

the contents of the file to hold them in place, 20 said means being adapted to be swung over to the rear of said closed side to form a support for the file, substantially as described.

8. A cabinet paper-file having one open and a closed side, and a swinging clasp or clamp 25 adapted to be swung over to the rear of the closed side to form a support for the file, said clamp having its side extended at an angle to its ends, and the ends forming a rest for the file when the clamp is swung over to the rear 30 of the closed side of said file, substantially as described.

In testimony whereof I affix my signature in presence of two witnesses.
